MILK BOTTLE CASE

John F. Maurer, Jr., North Bergen, N. J.

Application June 2, 1934, Serial No. 728,641

3 Claims. (Cl. 217—19)

This invention has general relation to boxes or crates and refers more particularly to an improved structure which is especially applicable to milk bottle cases.

5 The invention provides a case of the indicated character in which the vertical side and end walls, as well as the bottle supporting and partitioning elements, are so constructed and arranged that when they are combined with corner units of the type set forth, the case may be assembled without resorting to the use of rivets, nails, screws or equivalent fastening means, thereby admitting of the ready, complete or partial dis-assembly of the case in order to facilitate the removal and replacement or repair of broken or worn parts.

The invention further provides an improved case which embodies combined bottle supporting and partitioning elements which are fashioned to provide tenons protruding from the opposite ends thereof, which tenons are engageable within mortises formed in two vertical walls of the case for sustaining said elements in position and in assembled relation to the case.

25 The invention further comprehends an improved case of the character set forth in which the combined bottle supporting and partitioning elements are arranged in the case in a transverse position, whereby said members not only serve to more effectually isolate the bottles from any possible contact with each other but further function as means for efficiently bracing the longer side walls of the case against strains and stresses, thereby eliminating the necessity of employing additional bracing means.

30 The invention further resides in a crate or case structure of the type specified which is comparatively simple in its construction and mode of assembly, which may be economically produced and which is highly efficient for its intended purpose.

35 With the above enumerated and other more detailed objects and advantages in view, reference is now made to the following specification and accompanying drawings in which there is disclosed, by way of example, a preferred form of the invention, while the appended claims cover variations and modifications constituting equivalents thereof.

40 In the drawings:

45 Fig. 1 is a top plan view of a milk bottle case constructed in accordance with the present invention.

50 Fig. 2 is a longitudinal sectional view therethrough taken approximately on the line 2—2 of Fig. 1.

55 Fig. 3 is a transverse sectional view taken approximately on a plane indicated by the line 3—3 in Fig. 1.

60 Fig. 4 is a perspective view of one of the com-

bined bottle supporting and partitioning elements.

Fig. 5 is a fragmentary side view of the case illustrating the mortise and tenon connections between the vertical wall and the bottle supporting and partitioning element.

Figs. 6 and 7 are enlarged detail fragmentary horizontal sectional views taken approximately on the planes indicated by the lines 6—6 and 7—7 in Fig. 3 of the drawings.

10 Fig. 8 is a fragmentary vertical sectional view illustrating a supplemental support for the lower portions of the bottle supporting and partitioning elements.

Fig. 9 is a detail perspective view of the supplemental support shown in Fig. 8.

15 Referring to the drawings by characters of reference, the bottle case which is disclosed is illustrated as of the type in which the vertical side and end walls A and B are made up of a number 20 of pieces or slats, although it is to be understood that within the scope of the invention, said side and end walls may be made of solid pieces.

The side and end walls are connected and braced by corner units C, constructed in accordance with my prior United States Letters Patent, No. 1,885,748, granted November 1, 1932, which units C include angularly disposed hollow wings 25 designated generally by the reference characters D and E. The ends of adjacent vertical walls are embracingly received by the wings D and E and in order to retain the ends of said vertical walls within the corner unit, said wall ends are formed with vertical grooves F, while the wings are slotted to provide inturned tongues G engaging 30 within the grooves and constituting the sole means for holding the crate elements in assembled relation with each other, thus eliminating screws, nails, rivets or other equivalent fastening devices. This construction admits of the ready, 35 complete or partial disassembly of the case in order to facilitate the removal and replacement or repair of broken or worn parts by releasing the tongues G from the grooves F.

40 The case further includes combined bottle supporting and partitioning elements which are constructed of a length of material, preferably wood and which are of a length to extend between opposite vertical walls of the case, with their lower edges slightly above the plane of the bottom 45 edges of the vertical walls and extending upwardly therefrom an appropriate distance to serve as supports and partitions for the rows of bottles which are disposed between adjacent partition elements H and/or vertical walls of the 50 case. The partition elements are provided on their opposite longitudinal sides with arcuate recesses 55 which open through the upper edges of the elements and extend downwardly therefrom to a point spaced from the bottom edge to define 60

supporting ledges 11 upon which the bottoms of the bottles are designed to rest. The elements H carry at their opposite vertical end edges, one or more outwardly projecting tenons 12, in the present instance two being shown in vertically spaced relation. The tenons are fitted in mortises 13 provided in the opposite vertical walls so as to support the partition elements from said case walls without requiring screws, nails, rivets or other fastening elements and thereby greatly facilitating the assembly of the case and the incorporation of the elements H therein in a manner which allows for their removal without having to remove screws, rivets, or nails.

15 While obviously the bottle partitioning and supporting elements may be disposed either in longitudinal or transverse position, and supported from either the opposite vertical end walls or opposite vertical side walls, the present embodiment discloses the same as extending transversely of the case which is a departure from the present practice of utilizing two of said elements extending longitudinally. By disposing the elements H transversely, three of said elements are employed and the transverse arrangement of the elements serves to more effectually brace the lower portions of the longer side walls against inward buckling and bending strains which tend to crack or damage the walls.

20 The case may also include longitudinally disposed rods 14 which extend through openings 15 in the lower portion of the bottle supporting and partitioning elements H below the recesses 10 and the opposite ends of which rods are fitted in sockets 16 which open through the inner faces of the lower portion of the opposite vertical walls. In order to assist in supporting and partitioning the endmost rows of bottles, the inner face of the lower portion or slat of the opposite vertical walls is of greater thickness than the remainder to extend beyond the inner surface of the upper portion thereof and vertically extending arcuate depressions 17 are formed in the protruding portions or lower slats of the opposite vertical walls to define ledges 18 in alignment with the ledges 11 of the elements H. Obviously, by incorporating the rods 14 in the crate structure in the manner specified, said rods are assembled without riveting, thereby facilitating their emplacement and admitting of their ready removal if necessary.

25 In some instances where it is desired to dispense with the use of the rods 14, supplemental supports and reinforcing members J are provided for use in connection with the bottle supporting and partitioning elements H. The members J are preferably fashioned from sheet material and include a flat rectangular body 19 which is of a size and shape to snugly fit the ends of the elements H below the lowermost tenon 12 and which are affixed thereto by means of an instruck spur 20 driven into the end of the elements H. The body portion 19 is formed with marginal side flanges 21 and a marginal bottom flange 22 embracing opposite sides of the elements H and the lower surface thereof. The body is further provided with an outwardly directed upper flange 23 which underlies the lower surface of the lowermost tenon 12 and the free outer edge of the upper flange 23 is provided with an upwardly extending terminal 24 which

30 overlies the outer end face of the lowermost tenon 12. By virtue of the members J, the elements H are afforded a supplemental support from the vertical walls and in event of cracking or breaking of the lower portions of the elements H, the broken part will be retained in position. It is of course possible to utilize the members J in conjunction with the rods 14 if desired, but said members are particularly designed for use where the rods 14 are dispensed with.

35 What is claimed is:

1. A milk bottle case including vertical walls, corner units, interengageable tongue and groove means on the vertical walls and corner units for detachably connecting the same in assembled relation, combined bottle supporting and partitioning elements extending between opposite vertical walls and means for supporting said elements from said opposite walls comprising mortise openings in said walls and tenons projecting from opposite ends of said elements, fitted within the mortise openings of the walls and retained in place therein solely by the tongue and groove connection between the walls and corner units 20 and releasable upon disengagement of the tongue and groove connections for facilitating disassembly and reassembly of the vertical walls, corner units and combined bottle supporting and partitioning elements.

2. A milk bottle case including vertical walls, corner units, interengageable tongue and groove means on the vertical walls and corner units for detachably connecting the same together in assembled relation, combined bottle supporting and partitioning elements extending between opposite vertical walls, means for supporting said elements from said opposite walls comprising mortise openings in said walls and tenons projecting from opposite ends of said elements, fitted within the mortise openings of the walls, a plurality of rods extending transversely through openings in said elements and socketed portions of opposite vertical walls of the case within which the terminals of the rods are fitted, said bottle supporting and partitioning elements and said rods being retained in place solely by the tongue and groove means of connection between the walls and corner units.

3. A milk bottle case, including vertical side and end walls, corner units, interengageable tongue and groove means on the vertical walls and corner units for detachably connecting the same in assembled relation, combined bottle supporting and partitioning elements arranged transversely and in the direction of the width of the case and extending between the opposite vertical side walls thereof, and means for supporting said elements from said opposite walls comprising mortise openings in said walls and tenons projecting from opposite ends of said elements, fitted within the mortise openings of the walls and retained in place therein solely by the tongue and groove connection between the walls and corner units and releasable upon disengagement of the tongue and groove connections for facilitating disassembly and reassembly of the vertical walls, corner units and combined bottle supporting and partitioning elements.
